UNITED STATES PATENT OFFICE.

JOHN C. BOOTH, OF BROOKLYN, NEW YORK, ASSIGNOR TO J. H. WILLIAMS & CO., OF SAME PLACE.

WRENCH FOR PIPES, &c.

SPECIFICATION forming part of Letters Patent No. 532,192, dated January 8, 1895.

Application filed October 17, 1894. Serial No. 526,151. (No model.)

To all whom it may concern:

Be it known that I, JOHN C. BOOTH, a citizen of the United States, residing at Brooklyn, in the county of Kings and State of New 5 York, have invented an Improvement in Wrenches for Pipes, &c., of which the following is a specification.

Wrenches have heretofore been made in which elliptical and tapering jaws with teeth 10 on their edges have been combined with a chain that is wrapped around the pipe or circular article and retained by a hook or hooks. In this class of wrenches one end of the chain has been permanently fastened by a rivet or 15 screw so as to remain in a fixed position.

My present invention relates to the combination with a chain and jaws having teeth upon their edges and the handle connected with the jaws, of an end piece having lateral 20 projections that pass into grooves in the faces of the jaws so that the end that is permanently connected with the jaws can be slipped along to any desired position in relation to such jaws before or at the time that 25 the chain is wrapped around the pipe and hooked onto the jaws or handle, so that when the handle is moved to tighten the chain and to rotate the pipe, the end of the chain with its lateral projections will draw off sub- 30 stantially at right angles to the surfaces of the grooves into which such lateral projections are received and thereby the chain will be brought into contact with as large a surface around the pipe as it is possible and in- 35 crease the hold of the chain upon the pipe and lessen the risk of injury to the pipe, and the connections between the chain and the jaws with their lateral projections will slide or move along in the grooves when the 40 wrench is being applied to the pipe according to the size of the pipe and the position of the wrench to such pipe, and this gives great facility for applying the wrench, because the chain can be tightened in either direction 45 around the pipe according to the position of the pipe to the jaws and the movement of the handle.

In the drawings, Figure 1 is a side elevation of the wrench. Fig. 2 is a cross section at 50 the line $\alpha\alpha$ of Fig 1. Fig 3 is a plan view of

the wrench partly in section and without the chain. Fig. 4 is a cross section of a modification in the jaw and the shape of the end link, and Fig. 5 shows the face of one of the jaws with integral hooks.

55

The handle A is rigidly connected to the jaws B B' and advantageously such handle passes in between the jaws and into grooves in their inner surfaces, and the cross pin or bolt 2 permanently connects the jaws to the 60 handle. These jaws may be either circular or more or less elliptical or pointed and they are provided with teeth upon their edges.

In the surfaces of the jaws there are grooves 4 that are parallel or nearly so to the edges 65 of the jaws, and I prefer to make these grooves 4 upon the interior and opposite faces of the jaws, as shown in Figs. 1, 2, and 3, but where a single jaw B² is made use of the grooves 4 can be made upon the exterior surfaces of 70 such jaw and the handle A' can be forked at its end to pass into longitudinal recesses in the outer faces of the jaw B² so that the jaw B² can be slipped in between the jaw or prongs of the handle and secured by a bolt 75 or rivet.

The chain C is made of links of any desired character. I prefer and use plate links with transverse rivets, and the ends of the rivets may project so as to engage the hooks 5 upon 80 the jaws B B', or there may be any suitable hooks either upon the jaws or upon the handle to engage the chain, such for instance as the hooks in Patent No. 377,795, granted February 14, 1888, to J. H. Williams, or the hooks 85 in Patent No. 499,508, granted June 13, 1893, to Booth and Redfield, it being understood that any desired character of hooks or engaging devices for the loose end of the chain may be made use of in connection with the present 90 wrench. The end of the chain that is permanently fastened to the jaws is provided with a link D having lateral projections that enter the grooves 4. When the link D is adapted to pass in between the jaws, as in Figs. 1 and 95 2, the lateral projections 6 are on the outer edges of such link D and form with the same a T head, the projections passing in opposite directions into the grooves 4 in the inner faces of the jaws. Where the grooves are on 100

the outside of the jaw or jaws, as shown in Fig. 4, the link D' is made sufficiently wide to receive into it the edge of the jaw, and the lateral projections 7 extend inwardly toward each other so as to enter the grooves in the exterior faces of the jaw and near the edge thereof, and the link D or D' is permanently connected with the other links of the chain by the pivot pins or rivets in any desired manner. It will now be understood that the link D or D' can be slipped along into any desired position near the edge of the jaw or jaws, and the chain C extending from the link can be passed in either direction desired around the pipe or circular article and hooked to the jaws or handle, and as soon as the chain is tightened by a movement of the lever handle the lateral projections of the link will slide more or less within the grooves of the jaw so that such link will occupy a position nearly perpendicular to the edge of the jaw and will allow the chain to encircle the pipe and press evenly upon its surfaces, and at the same time the teeth in the edge of the jaw will press into such pipe to a sufficient extent to insure the rotation of such pipe by the wrench.

I have represented at 8 by dotted lines hooks upon the handle A, but I sometimes make 30 hooks 9 by slots cut directly into the edges of the jaws B or B' at one or both sides of the handle and near to such handle (see Fig. 5) so as to form a direct and reliable connection between the chain and the jaws.

35 Where but one jaw is shown, as illustrated in Fig. 4, the chain lies upon the periphery or exterior edges of such jaw, but where two jaws are used, as shown in Figs. 1 and 2, the chain itself may pass in between such jaws 40 and the projecting pivot pins of such chain may lie against the surfaces of the jaws so as to allow for the projecting ends of the pivot pins passing into the slots and being received by the hooks upon the edges of such jaws.

45 In Figs. 1 and 3 I have shown the hooks 5 upon separate plates B³ grooved to set upon the sides of the handle and resting at their edges against the back edges of the jaws and secured by a cross bolt 10 as this construc-

tion allows for the removal of any injured 50 part of the wrench.

I claim as my invention—

1. The combination with the lever handle and chain in a wrench, of a jaw permanently connected with the handle and having grooves 55 in its faces parallel or nearly so with the edges of the jaw, and a link connected at one end to the chain and having lateral projections at or near the other end to pass into the grooves of the jaw, substantially as set forth. 60

2. The combination with the handle and chain in a pipe wrench, of two jaws secured at one end of the handle and at opposite sides thereof and having grooves in their inner faces parallel or nearly so with the edges of 65 the jaws, and a link connected with one end of the chain and having lateral projections forming a T head, which projections pass into grooves in the inner faces of the jaws, substantially as set forth. 70

3. The combination in a wrench, of a handle, two jaws permanently connected at one end of the handle and having grooved surfaces and hooks upon the edges of the jaws adjacent to the handle, a chain having projections adapted to engage the hooks on the jaws that are adjacent to the handle, and a link at one end of the chain having lateral projections to pass into the grooves of the jaws, 75 substantially as set forth. 80

4. The combination with a handle, of two jaws that are nearly circular and recessed upon their inner faces to receive the handle, and a cross pin or rivet for securing the parts together, the jaws having grooves in their 85 faces parallel or nearly so to the edges of the jaws, a chain adapted to pass around the pipe, and an end link to the chain having lateral projections that engage the grooves in the jaw, and means for hooking the chain to the 90 jaw or handle after the chain has been passed around the pipe or other article, substantially as set forth.

Signed by me this 9th day of October, 1894.
JOHN C. BOOTH.
